CHAIN WASHING DEVICE

Floyd B. McKneely, Great Kills, N. Y.

Application July 2, 1946, Serial No. 681,088

3 Claims. (Cl. 114—179)

1

This invention relates to a device for cleaning the anchor chains of floating equipment and vessels such as ships, tankers, barges, and the like. More particularly, the invention is concerned with a system of nozzles for ejecting water or other cleaning liquid to remove foreign matter from anchor chains after the latter have been submerged in navigable waters.

Heretofore in the cleaning of anchor chains, the usual practice has been to water-wash the chain as it is being drawn up into the vessel with a hand hose. Due to the adherent nature of the foreign matter, such as mud, slime, etc., clinging to the chain, a stream of water of fairly large diameter and under a substantially high pressure is necessary. Such a high pressure water stream is dangerous to handle with a hand hose, requiring the cautious attention of at least one operator. Even with water under high pressure, complete removal of the foreign matter by washing with a single stream is difficult to attain. Moreover, a portion of the mud, etc., removed is invariably washed up onto the deck of the vessel along with some of the wash water, requiring an additional removal of this secondary deposition.

It is an object of the present invention to provide a device for cleaning anchor chains without the aforesaid difficulties. It is a further object to provide an efficient means for removing foreign matter adhering to anchor chains. A still further object is the provision of a system of nozzles for effectively washing anchor chains. These and other objects which will be apparent to those skilled in the art are attained in accordance with the present invention.

It has been found, in accordance with this invention, that an effective system for cleaning anchor chains can be installed along the path through which the anchor chain passes. The device of this invention accordingly comprises a hawse pipe sloping downwardly and outwardly from the forecastle deck of the vessel to the side of the vessel's hull. A number of nozzles are positioned along the circumference of the hawse pipe and are adapted to direct streams of wash liquid toward the lower internal surface of the hawse pipe so that a chain being drawn upwardly through said pipe may be washed free of foreign matter adhering thereto. The foreign matter thus removed passes down and out of the hawse pipe.

The invention may be more readily understood by reference to the attached drawing.

Figure 1 is a partial cross sectional view of a

2

vessel in which the cleaning device of this invention is installed.

Figure 2 is a longitudinal section taken along the line 2—2 of the hawse pipe shown in Figure 1.

Figure 3 is a horizontal section taken along the line 3—3 at right angles to the axis of the hawse pipe shown in Figure 1.

Referring now to Figure 1, hawse pipes 1 and 2 slope downwardly and outwardly from the forecastle deck 18 to the side of the vessel's hull 19. Along the circumference of hawse pipes 1 and 2 are positioned a number of nozzles 7, 8, 9 and 4, 5, 6, respectively. Water or other cleaning liquid is drawn through conduit 10, which conveniently may be the fire line of the vessel. Liquid passes under pressure through control valve 11, which diverts part of the stream through conduit 12 and part through conduit 13. The liquid stream which passes through line 12 is separated into a plurality of streams passing through conduits 14, 15, and 16 directed into the interior of hawse pipe 2 through nozzles 4, 5, and 6, respectively. In a similar manner the liquid stream passing through line 13 is diverted into three streams and directed through nozzles 7, 8, and 9 to the interior of hawse pipe 1. The nozzles are directed downward, either vertically or at a small angle to the vertical to avoid splashing of the liquid on the deck of the vessel and to obtain an optimum washing effect of the anchor chain.

In Figure 2 a longitudinal section taken along the line 2—2 of Figure 1 is shown and in Figure 3 a horizontal cross section taken along the line 3—3 is shown. It is to be noted from these views that one of the liquid streams, namely, that passing through line 15 and nozzle 5, is directed vertically downward toward the lower internal surface of the hawse pipe and strikes the anchor chain 17 between the links thereof in a straight line, thereby effectively removing foreign matter adhering to said links. The remaining secondary streams passing through lines 14 and 16 and nozzles 4 and 6 are directed at an angle to the vertical stream issuing from line 15 and nozzle 5. It has been found, in accordance with this invention, that the arrangement of nozzles as shown is to be preferred. It has been further discovered that the angle which the secondary streams make with the vertical primary stream must be taken into consideration if the utmost cleaning efficiency of the anchor chain is to be attained. Thus, it has been found that when the projections of the primary vertical stream and the secondary angular streams on the vertical plane passing through the axis

of the hawse pipe intersect at an angle of about 15°, foreign matter adhering to the chain is effectively removed, said chain lying along the lower internal surface of the hawse pipe and being washed by the primary and secondary liquid streams. While the above angle of about 15° is to be preferred, the path of streams may have projections on the vertical plane through the axis of the hawse pipe, intersecting over a range of from about 5 to about 25° to effect a substantially complete removal of the mud, slime, etc., adhering to the chain.

The device of this invention has been shown with three nozzles and generally this number is adequate for an effective cleaning under ordinary circumstances. However, it will be understood that a greater number of nozzles angularly spaced about the circumference of the hawse pipe may be employed if desired. In accordance with the preferred embodiment of this invention, however, it is necessary that at least one of the liquid streams impinge on the anchor chain in a downward vertical line and that the remaining secondary streams make a small angle to the vertical stream to provide a zone of liquid through which the anchor chain passes as it is drawn up along the lower internal surface of the hawse pipe into the vessel.

The anchor chain, in accordance with the present invention, is subjected to three distinct washings. First, the chain is washed by a flow of liquid down the hawse pipe as it is being drawn up. Secondly, the anchor chain is washed by a primary vertical stream impinging on the anchor chain from above, said chain lying in the form of an X along the lower internal surface of the hawse pipe. This primary stream passes through the links of the chain and removes a substantial proportion of the foreign matter adhering thereto. However, this stream alone is not sufficient to completely wash the anchor chain free of matter clinging to the sides of the chain links. Such remaining matter is removed in accordance with the present device by angular streams of liquid striking the sides of the chain and passing through the links thereof to effectively remove remaining matter adhering after the chain has been subjected to the flow of liquid down the hawse pipe and the vertical liquid stream. The chain, after being washed on its underside by the flow of liquid down the hawse pipe, on its topside by the vertical liquid stream, and on its sides by the angular liquid stream, is thus substantially completely washed free of foreign matter.

Water, being inexpensive and readily available, will ordinarily be employed as the washing liquid. It will be understood, however, that the present invention also contemplates the use of other cleaning liquids. Aqueous or other liquid solutions of various materials may thus be used to facilitate cleaning of anchor chains in accordance with the present invention.

I claim:

1. A device for cleaning the anchor chain of a vessel comprising in combination, a hawse pipe, sloping downwardly and outwardly from the deck of said vessel to the side of said vessel's hull, a plurality of circumferentially spaced openings piercing the wall of said hawse pipe, a plurality of nozzles, one interfitting into each of said openings, and means to supply liquid under pressure to each of said nozzles, one of said nozzles being so positioned as to direct a stream of liquid ensuing therefrom in a downward vertical line onto an anchor chain drawn upwardly through

said hawse pipe, the remaining nozzles being angularly spaced on either side of the aforementioned nozzle, whereby streams of liquid ensuing therefrom impinge on either side of said anchor chain, so that said chain being drawn upwardly through said hawse pipe is washed on its underside by a flow of liquid passing down the hawse pipe, on its topside by the liquid stream ensuing from said vertically positioned nozzle and on its sides by the liquid streams ensuing from said angularly positioned nozzles.

2. A device for cleaning the anchor chain of a vessel comprising in combination, a hawse pipe, sloping downwardly and outwardly from the deck of said vessel to the side of said vessel's hull, a plurality of circumferentially spaced openings piercing the wall of said hawse pipe, a plurality of nozzles, one interfitting into each of said openings, and means to supply liquid under pressure to each of said nozzles, one of said nozzles being so positioned as to direct a stream of liquid ensuing therefrom in a downward vertical line onto an anchor chain drawn upwardly through said hawse pipe, the remaining nozzles being angularly spaced on either side of the aforementioned nozzle, whereby streams of liquid ensuing therefrom impinge on either side of said anchor chain, the projections of said vertical and said angular streams on the vertical plane passing through the axis of said pipe intersecting at an angle between about 5 and about 25°, so that said chain being drawn upwardly through said hawse pipe is washed on its underside by a flow of liquid passing down the hawse pipe, on its topside by the liquid stream ensuing from said vertically positioned nozzle and on its sides by the liquid streams ensuing from said angularly positioned nozzles.

3. A device for cleaning the anchor chain of a vessel comprising in combination, a hawse pipe, sloping downwardly and outwardly from the deck of said vessel to the side of said vessel's hull, a plurality of circumferentially spaced openings piercing the wall of said hawse pipe, a plurality of nozzles, one interfitting into each of said openings, and means to supply liquid under pressure to each of said nozzles, one of said nozzles being so positioned as to direct a stream of liquid ensuing therefrom in a downward vertical line onto an anchor chain drawn upwardly through said hawse pipe, the remaining nozzles being angularly spaced on either side of the aforementioned nozzle, whereby streams of liquid ensuing therefrom impinge on either side of said anchor chain, the projections of said vertical and said angular streams on the vertical plane passing through the axis of said pipe intersecting at an angle of about 15°, so that said chain being drawn upwardly through said hawse pipe is washed on its underside by a flow of liquid passing down the hawse pipe, on its topside by the liquid stream ensuing from said vertically positioned nozzle and on its sides by the liquid streams ensuing from said angularly positioned nozzles.
